Primary Examiner — Cynthia Ramirez*Assistant Examiner* — Michael A Maharajh(74) *Attorney, Agent, or Firm* — Daniel A. Thomson; Emerson Thomson Bennett, LLC(57) **CLAIM**

The ornamental design for a muscle diastole apparatus, as shown and described.

DESCRIPTION

FIG. 1 is a perspective view of a muscle diastole apparatus; FIG. 2 is a front view of a muscle diastole apparatus; FIG. 3 is a rear view of a muscle diastole apparatus; FIG. 4 is a left side view of a muscle diastole apparatus; FIG. 5 is a right side view of a muscle diastole apparatus; FIG. 6 is a top plan view of a muscle diastole apparatus; and, FIG. 7 is a bottom view of a muscle diastole apparatus.
